UNITED STATES PATENT OFFICE.

STEPHEN PRIEST, JR., OF WEST DEVONPORT, TASMANIA, AUSTRALIA.

WALL-TIE.

No. 903,000.

Specification of Letters Patent.

Patented Nov. 3, 1908.

Application filed January 12, 1906. Serial No. 295,804.

To all whom it may concern:

Be it known that I, STEPHEN PRIEST, Jr., a subject of the King of Great Britain, residing at West Devonport, in the State of Tasmania, Commonwealth of Australia, have invented a new and useful Improved Wall-Tie or Means for Holding Together the Two Divisions of Cavity Brick Walls; and I do hereby declare the following to be a full, clear, and exact description of the same.

My invention has been devised in order to provide a tie for hollow walls, which will not only tie both divisions of the hollow wall securely together, but will also strengthen each division longitudinally.

My tie consists of two or more longitudinal wires which are connected together by two wires (hereinafter called the transverse wires) one of each of these being twisted around each longitudinal wire for a certain distance, and both being then carried across the space intervening between the longitudinal wires, so that they cross one another at an angle about midway between said longitudinal wires. The transverse wire twisted around the right hand longitudinal wire is then twisted round the left hand longitudinal wire for a certain distance, and carried across again to the right hand longitudinal wire. The other transverse wire twisted around the left hand longitudinal wire, is carried across and twisted around the right hand longitudinal wire, the operation being repeated until a tie of predetermined length is completed. At a point where the transverse wires cross one another between the longitudinal wires, they are twisted together to increase the strength of the tie.

The drawing shows a plan of a portion of a tie constructed according to my invention, showing the transverse wires twisted together where they cross the cavity in the wall.

1 is the hollow wall.

2 and 3 are the longitudinal wires which run parallel with each other.

4 and 5 are twisted round the longitudinal wires 2 and 3 respectively for any suitable distance, and then the transverse wire 4 is taken across to the longitudinal wire 3, and transverse wire 5 is taken across to the longitudinal wire 2. Said wires 4 and 5 are twisted round wires 2 and 3 for the required distance, and then passed back to the wires 2 and 3 respectively. The transverse wires 4 and 5 are passed backwards and forwards in this manner until a tie of a predetermined length is made. The said transverse wires 4 and 5 are twisted together where they cross each other between the longitudinal wires 2 and 3 as shown at 6 in Fig. 1.

In erecting a hollow wall, my tie is cut to the length required and may be laid in the mortar upon every fourth or sixth course of bricks, so that the longitudinal wires 2 and 3 run from end to end along the center of each division of the hollow wall 1.

Having now fully described and ascertained the nature of my said invention, and in what manner the same is to be performed, I declare that what I claim is:

In combination with a hollow wall, a tie comprising longitudinal wires 2 and 3, and wires 4 and 5 twisted respectively around said longitudinal wires for a certain distance, both being then twisted together and carried across the intervening space between said longitudinal wires when each is twisted around the opposite longitudinal wire, said wires 4 and 5 coming together within the wall so as to form triangular spaces between themselves and the longitudinal wire in which the material of the wall enters.

In testimony whereof, I have signed this specification in the presence of two subscribing witnesses.

STEPHEN PRIEST, JR.
